MARKING DEVICE

Fred G. Dressel, Buffalo, N. Y., assignor of one-half to Rollinson W. Poucher, Buffalo, N. Y.

Application February 11, 1950, Serial No. 143,731

4 Claims. (Cl. 15—140.3)

1

This invention relates to marking devices and particularly to such devices which are adapted for use in painting signs, placards, and the like.

It is an object of the invention to provide a marking device which is easy to use and is self-filling during periods of non-use.

Another object of the invention is to provide a marking device in which the flow of marking fluid is regulated automatically but may be varied if desired.

A further object of the invention is to provide a marking device which is of simple and inexpensive construction and which has no parts which may get out of order.

Still another object of the invention is to provide a marking device which is compact and which may readily be carried from place to place without danger of leakage or spilling.

Additional objects of the invention will be evident from the following specification taken in conjunction with the drawings, in which:

Figure 1 is an elevational view of a marking device constructed in accordance with the present invention;

Figure 2 is a view similar to Figure 1, but with the base or reservoir of the marking device shown in section;

Figure 3 is a view, taken on the line 3—3 of Figure 1, which is similar to Figure 2 but shows the entire marking device in section;

Figure 4 is a horizontal sectional view on line 4—4 of Figure 1;

Figure 5 is a horizontal sectional view on line 5—5 of Figure 1; and

Figure 6 is an enlarged fragmentary view similar to Figure 3 with the tip or nib of the brush turned through 90 degrees.

The novel marking device of the present invention comprises two principal parts, a base or reservoir 10 and a brush 11 which are adapted to fit and be used together, thus constituting a unit.

The reservoir 10 is cup-like and is preferably formed of glass, plastic material or of corrosion resistant metal. The reservoir as it is depicted in the drawings is circular in cross section with an open top, but it will be understood that reservoirs having cross sections of any desired shape may be used. On the exterior of its upper end, adjacent the open top thereof, the reservoir 10 is preferably provided with molded or cut threads 14. A closure comprising a screw-type cap 15 having threads 16 corresponding to those on the reservoir 10 is provided for the open top of the latter. The cap 15 is provided, preferably

2

at the center thereof, with an opening. Surrounding the opening on the concave or lower face of the cap 15 there is provided an annular reinforcing ring 18 which may be secured to the cap in any suitable way or, if desired, may be formed integrally therewith as an axially extending, downwardly-directed flange around the edge of the opening. The cap 15 is preferably formed of metal but other suitable materials may be used.

Fitting within the opening in the cap 15 and extending downwardly into the marking fluid 19 in the reservoir 10 when the cap is in position on the top of the reservoir is a feeder tube

15 20. The tube 20 is preferably cylindrical in shape and is provided on its open upper end with an outwardly turned, annular bead or flange 21 which serves as a stop on the top of the cap 15 to prevent the tube from passing completely through the opening in the cap. Preferably the tube 20 is constructed of metal or durable plastic material. When the tube 20 is in position and the cap 15 is screwed in place on the reservoir 10, the open bottom of the tube preferably extends more than half way to the bottom of the reservoir 10.

Held within the tube 20 there is a porous, resilient, absorbent filler 22. The filler 22 does not entirely fill the tube 20 but leaves in the upper end thereof a well 23. The lower end of the filler 22 preferably extends beyond the lower end of the tube 20 to a point in close proximity to the bottom of the reservoir 10. Various materials may be used in forming the filler 22, such as, for example, either natural or cellulose sponge, foam rubber, or felt. The latter, however, is preferred as it is obtainable in a large number of grades so that the proper absorbency and resiliency may be readily obtained. A plurality of slits 24 are provided in the sides of the feeder tube 20 which permit free access of the marking fluid in the reservoir 10 to the portion of the filler within the tube.

Although the brush 11 is shown in the drawings as having a tubular barrel 26 which is cylindrical in shape, it may, of course, be formed in other shapes if desired. The barrel 26 is, however, preferably constructed of flexible plastic material such as, for example, cellulose acetate or polyethylene, and it is elongated to facilitate the grasping of the brush by the user. One end 27 of the barrel 26 of the brush 11 is closed while the other end is open and is flared outwardly to provide an annular bead or flanged rim 28. The tubular barrel 26 is filled from a point near

the open end thereof for the major portion of its length with a porous, resilient packing 29 which has a high degree of absorbency for marking fluid.

The brush 11 also comprises a nib or applicator 30. The latter has one end of the proper size and shape to fit securely within the open end of the barrel 26 while its other end is enlarged and may be of any shape desired for proper and convenient application of marking fluid to surfaces. For general use a wedge-shaped nib has been found to be very satisfactory. The nib 30 may be formed of any desired porous, resilient, absorbent material but it is preferred to use a somewhat harder and heavier grade of felt than is used for the packing 29 so that it will be less easily deformed during use. The end of the nib 30 within the barrel 26 should be in direct contact with the packing 29 therein in order to obtain proper filling of the brush with marking fluid and proper flow of the latter to the nib when the brush is being used.

The marking device of the present invention may be used with marking fluids of a variety of types. It is preferred, however, to use a fluid which does not become gummy on drying so as to avoid clogging of the pores of the filler 22, the packing 29 and the nib 30. It is also desirable to use a fluid of low viscosity as the operation of the marking device is less effective when a viscous marking fluid is used. Ink and other marking fluids having water vehicles have been found very satisfactory. It is, of course, possible to have the fluid of any desired color.

The operation of the improved marking device described above is as follows. Marking fluid is placed in the reservoir 10 and the cap 15 is screwed in place with the feeder tube 20 extending down into the marking fluid and at least a portion of the porous filler 22 held in the tube 20 immersed in the fluid. By capillary action the marking fluid is carried to the portion of the filler 22 which is not immersed in the marking fluid and the whole of the filling becomes saturated. When, therefore, the nib 30 of the brush 11 is inserted in the well 23 at the upper end of the feeder tube 20 and is pressed into firm contact with the filler 22, as shown in Figures 3 and 6, the marking fluid from the saturated filler will be drawn by capillary action through the nib 30 into the absorbent packing 29 in the tubular barrel 26 of the brush and, by saturating the packing, provide a supply of marking fluid in the brush. An orifice 32 is provided in the side wall of the tubular brush barrel 26 near the closed end 27 to allow escape of air as it is displaced by the marking fluid rising in the porous packing 29 and permit entrance of air as marking fluid is withdrawn when the brush is used.

It will be noted that the bead 28 on the open end of the tubular barrel 26 of the brush 11 is in close contact with the inner face of the feeder tube 20 and thus serves to minimize evaporation of the marking fluid from the brush and reservoir when the brush is in place as shown in the drawings. It also serves to steady the brush and to reduce the chance of its accidentally falling out.

When it is desired to use the brush 11 in marking, for example in making a sign or placard, the nib 30 of the brush is applied to the surface which is to be marked. Any desired characters may be brushed, painted, or daubed on the surface, the wedge shape of the preferred nib design 30 being capable of providing either broad or narrow lines

as desired. When the brush is no longer required, it is returned to position, as shown in the drawings, in the well 23 of the reservoir 10. The supply of marking fluid in the brush is thereupon replenished by capillary action which carries the fluid from the reservoir through the filler 22 in the feeder tube 20 and the nib 30 into the packing 29 in the barrel 26. Thus, there is always assured a supply of marking fluid in the brush when needed.

Where a faster rate of flow of marking fluid to the nib 30 of the brush 11 is desired than is available by capillary action, the user may obtain a temporarily increased flow by closing the orifice 32 with one finger while at the same time gently squeezing the tubular barrel 26 of the brush, thus forcing marking fluid from the packing 29 in the barrel into the nib where it is available for use. The reverse of this action may also be of use in the event prolonged use of the brush has substantially exhausted the marking fluid therein. In such a case, the fluid in the brush may be replenished more quickly than it would normally be filled by capillary action by the following simple procedure. The tubular barrel 26 of the brush 11 is squeezed to compress it and then, while a finger is held over the orifice 32, the nib 30 of the brush 11 is pressed against the filler 22 in the feeder tube 20. The pressure on the tube is then released while the orifice 32 remains closed, thus producing a rapid flow of marking fluid into the packing 29 of the brush as a result of the reduced pressure in the barrel 26.

The marking device of the present invention is a noteworthy improvement over prior marking devices of the same general type. In the first place, the brush is self-filling when placed in the base or reservoir. At the same time, since the marking fluid in the barrel of the brush is held in the pores of the absorbent felt packing, no fluid will run out if the brush is tilted. The large amount of marking fluid held by the packing in the brush makes for convenience in marking or writing. However, since the fluid is fed to the nib gradually by capillary action there is no tendency for the brush to form blots or pools of marking fluid.

In the second place, when the marking device is assembled with the brush in the well at the top of the filler tube of the receptacle, evaporation of the marking fluid is substantially prevented by the snug fit of the annular bead at the open end of the barrel of the brush in the feeder tube. Further, this snug fit and the porous, absorbent filler in the reservoir combine to restrict the flow of marking fluid from the reservoir so that, even if the marking device is overturned, there will be little or no leakage.

In addition, as previously pointed out, the reservoir may be formed of metal or plastic material, neither of which are easily broken, and the barrel of the brush is preferably formed of a flexible plastic material. Accordingly, the marking device will be unlikely to be damaged by the shocks and rough handling or dropping which not infrequently occur during transportation in a truck or otherwise. It should also be noted that the present marking device requires no cleaning in ordinary use and is always ready for use.

It will be appreciated that the reservoir may be transparent or translucent and thus the level of the marking fluid therein may be readily seen so that it may be refilled before the marking fluid is exhausted. The color of the marking fluid in a marking device constructed in accordance

with the present invention may be indicated in any suitable way as by painting or otherwise coloring either the reservoir or the brush barrel or, if desired, either or both of these parts may be of clear, uncolored material so that the color of the fluid contents may be seen.

The resilience and porosity of the felt preferably used in forming the porous, absorbent, resilient filler 22, packing 29 and nib 30 of the marking device may be chosen to suit the needs of a particular user or the demands of a particular type of use. Thus for a use in which very free flow for frequent short intervals of time is required, as contrasted with average use, the felt should be somewhat softer and more porous so that the marking fluid will feed to the nib more rapidly than would be the case with a harder, denser felt, and furthermore, the brush will be refilled more rapidly when it is replaced in the reservoir.

Although, as shown in the drawings, the filler in the feeder tube 20 and the packing in the barrel 23 of the brush 11 are formed in small sections, this is not essential and either or both of these elements may be formed as unitary members, if desired. It will be understood that the packing 29 and filler 22 may be replaced, if desired, by other porous, resilient, absorbent material or by felt of a different grade. The nib 30 may also be easily replaced whenever desired by a nib of different shape, material, or marking characteristics.

I claim:

1. A self-filling marking device comprising in combination a reservoir adapted to contain marking fluid and a brush removably carried in said reservoir, said reservoir comprising a cap, a filler tube having an open end extending through said cap and the other end extending into said reservoir, a slit in the side wall of said tube, and a porous, resilient, absorbent filler within said tube adapted to absorb marking fluid contained within said reservoir, said brush comprising an elongated, one-piece, flexible tubular barrel closed at one end and having its open end disposed within said tube, a porous, resilient, absorbent packing within the open end of said barrel and providing an unfilled chamber at the closed end of said barrel, a porous, resilient, absorbent nib in contact with said packing and extending outwardly from the open end of said barrel, and a finger opening through the wall of said barrel and communicating with said chamber and adapted to be closed by the user's finger before or after compression of said flexible barrel to establish a condition of pressure or vacuum in said barrel.

2. A self-filling marking device comprising in combination a reservoir adapted to contain marking fluid and a brush removably carried in said reservoir, said reservoir comprising a cap, a cylindrical filler tube open at both ends and having one end extending through said cap and the other end extending into said reservoir, and a porous, resilient, absorbent filler within said tube adapted to absorb marking fluid contained within said reservoir, said brush comprising an elongated, one-piece, tubular barrel of flexible material having an open end provided with a radially outwardly extending bead fitting closely within said tube, a porous, resilient, absorbent packing within said barrel, and a nib of porous,

resilient, absorbent material in contact with said packing and extending outwardly from said open end of said barrel.

3. A self-filling marking device comprising in combination a reservoir adapted to contain marking fluid and a brush removably carried in said reservoir, said reservoir comprising a cap, a filler tube open at both ends and having one end extending through said cap and the other end extending into said reservoir, and a porous, resilient, absorbent filler within said tube adapted to absorb marking fluid contained within said reservoir, said brush comprising an elongated, one-piece, tubular barrel of flexible material closed at one end, an outwardly projecting integral annular flange at the open end of said barrel and closely fitting within said tube, a porous, resilient, absorbent packing within the open end of said barrel and providing an unfilled chamber at the closed end of said barrel, a nib of porous, resilient, absorbent material in contact with said packing and extending outwardly from the open end of said barrel, and a finger opening through the wall of said barrel and communicating with said chamber and adapted to be closed by the user's finger before or after compression of said flexible barrel to establish a condition of pressure or vacuum in said barrel.

4. A self-filling marking device comprising in combination a reservoir adapted to contain marking fluid and having an opening in the top thereof, a cap for said opening threadedly engaging said reservoir, a filler tube open at both ends depending from said cap and having one of said ends opening through said cap, said tube having slits in the side wall thereof, a porous, resilient, absorbent filler within said tube and occupying a substantial portion of the length thereof, said filler extending beyond the lower end of said tube and being adapted to absorb marking fluid contained in said reservoir, a brush removably carried in said tube and having an elongated, one-piece, tubular barrel of flexible material closed at one end, the open end of said tubular barrel being enlarged to fit closely within said tube, a porous, resilient, absorbent packing within the open end of said barrel and providing an unfilled chamber at the closed end of said barrel, and a nib of porous, resilient, absorbent material extending outwardly from the open end of said barrel, said nib being in firm contact with said packing and being adapted to directly contact said filler when said brush is inserted in said tube, and said barrel being provided with a finger opening through the wall thereof and communicating with said chamber and adapted to be closed by the user's finger before or after compression of said flexible barrel to establish a condition of pressure or vacuum in said barrel.
